HERMAN NIELSEN, OF COPENHAGEN, DENMARK.

OUTFLOW-REGULATOR.

1,296,208.

Specification of Letters Patent.

Patented Mar. 4, 1919.

Application filed February 6, 1917. Serial No. 146,977.

To all whom it may concern:

Be it known that I, HERMAN NIELSEN, Ingemansvej No. 9, Copenhagen, Denmark, have invented certain new and useful Improvements in Outflow-Regulators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to apparatus for regulating the outflow of a fluid from a container, the same being especially designed for use in connection with oil cups or lubricators for machinery.

It is a well known fact that with gravity feed lubricators of this kind, the flow of the oil from the outflow or discharge opening decreases in volume with a decrease in the hydrostatic pressure or in the quantity of oil in the cup or container. The object 25 of my invention is to provide means for regulating or controlling the outflow of such oil so that it will at all times be substantially the same, notwithstanding variations in the level of the oil in the container. A further object of the invention is to provide 30 means for adjusting the device whereby the speed or volume of outflow may be increased or decreased and whereby variations in the density of the liquid whose flow is controlled, may be compensated for.

Other objects of the invention will hereinafter appear and the novel features thereof will be set forth in the claims.

In the drawing forming part of the specification:

Figure 1 is a sectional elevation of an oil cup or lubricator embodying my invention; and

Fig. 2 is an elevation of a modified form 45 of buoyant member; and

Fig. 3 is a detail view.

The oil cup or container 1 may be of any usual or preferred construction. As shown, it has extending centrally through it a vertically disposed tube 2 which projects down below the lower end of the cup or container 1 where it is contracted in shape and provided with a discharge or outflow opening 3. The said tube is also provided at points 55 slightly above the bottom of the cup or container 1 with lateral ports or passages 4.

The said tube extends upwardly above the top of the container 1 and is provided with screw threads 5. Screwed upon the upper projecting end of the tube 2 is a cap 6 having a central axial opening therein, and upon said cap is mounted an inverted U-shaped frame or support 7. Located within the tube 2 is a buoyant member or float 8, the same being shown as cylindrical in form. This buoyant member is preferably made of metal or other material of greater specific gravity than the oil or other liquid 9 in the container 1. The lower end of the buoyant member 8 has a contracted neck 10 forming a shoulder 11 and carrying a downwardly opening valve 12 which controls the flow of oil or other fluid through the discharge opening 3. The shoulder 11 is adapted to coöperate with a seat 13 in the contracted portion of the tube 2 for the purpose of cutting off entirely the flow of liquid through the opening 3 when the device is not in use. The buoyant member 8 is supported by or suspended from a coil spring 14 which is secured to the upper end of said buoyant member, and is also secured to a cylindrical block 15 which extends through the axial opening in the cap 6. The said block is capable of being turned 80 and moved longitudinally of said opening. It is normally supported from the inverted U-shaped frame or bracket 7 upon two studs 16 which are screwed into and extend inwardly from the vertical members of the frame 7 and fit into L-shaped slots 17 in the upper end of the block 15. In Fig. 1 the studs 16 are shown as located in the horizontal portions of the slots 17 and the buoyant member 8 is supported with the shoulder 11 thereon elevated away from the seat 13 surrounding the discharge opening 3. By turning the block 15 until the studs 16 come opposite the vertical portions of the slots 17, the said block, and with it the buoyant member 8, may be lowered until the shoulder 11 is brought into engagement with the seat 13 and the outflow opening 3 completely closed. This operation will be effected when the lubricator 1 is not in use and it is desired to prevent any flow of oil therefrom.

Extending vertically through a central opening in the block 15 is a rod or spindle 18 having a knob or handle 19 at its upper end by means of which it may be turned 110 and having a screw 20 upon its lower end which fits within the coils of the spring 14.

The said screw 20 has been shown as a block or enlargement on the lower end of the rod 18 having an external outwardly extending spiral rib 21 thereon. This rib has been shown 5 as fitting between two adjacent coils of the spring 14. The purpose of the screw 20 is to adjust the spring 14 so as to vary the elasticity thereof or rather the extent of effectiveness of said spring on the buoyant member 8. It will be understood that the only 10 portion of the spring 14 which is effective upon the buoyant member 8 is that below the screw 20. By turning said screw downwardly, the portion of the spring 14, which 15 is effective upon the buoyant member 8, is reduced, whereas by turning the screw 20 upwardly the effective portion of the spring 14 is increased.

The buoyant member 8 being submerged 20 in the oil or other liquid in the container 1, is partially sustained by such oil or other liquid and partially by the spring 14. It can readily be understood that if a buoyant member were employed which was sustained 25 wholly by the liquid in the container and which also had the outflow valve 12 connected to it, such buoyant member would fall with the liquid in the container as its level lowered, but the movement of the 30 buoyant member and consequently of the valve carried thereby would be to the same extent that the level of the liquid lowered. This would result in a too rapid opening of 35 the valve controlling the outflow opening and would not bring about a constant outflow under variations in level or hydrostatic pressure. It is necessary, in other words, in order to bring about this result, that the downward movement of the buoyant member carrying the valve controlling 40 the outflow opening be less than the downward movement in the level of the liquid. It is to accomplish this result that I provide for the support of the buoyant member 8 45 on the spring 14. For while the buoyant member 8 carrying the valve 12 will drop with a lowering of the level of the liquid 9, due to the fact that it is partially sustained by the said liquid, its downward movement 50 is resisted by the spring 14 so that it will not fall to as great an extent as the level of the liquid, but will fall just so much as to open the valve 12 to just such an extent as to 55 compensate for the decrease in the hydrostatic pressure and bring about an equalization in the outflow regardless of changes in level or hydrostatic pressure in the liquid. The adjustment of the spring 14 to vary the extent of the effective portion of said spring 60 on the buoyant member 8 enables me to regulate the sustaining power of the said spring so as to bring about the proper relative movement of the buoyant member 8 with 65 respect to the movement of the level of the liquid 9. The position of the valve 12 with

respect to the outflow opening 3 may be adjusted by turning the cap 6 either up or down on the upper end of the tube 2. This adjustment, as well as the adjustment of the spring 14, enables me to adapt the device for 70 use under varying conditions and with different liquids. That is to say, I am able to adapt the device for use with dense or light liquids or for the purpose of obtaining a greater or less regulated volume of outflow 75 from the same.

The cylindrical form of the buoyant member 8 is particularly well adapted for use in connection with oil cups or lubricators for machinery, but with other fluids than oil or 80 where greater outflow speeds are required, it may be desirable to change the shape of the buoyant member. One variation in shape which may be made, is illustrated in Fig. 2 of the drawing in which 8^a indicates 85 the buoyant member and 12^a the valve at the lower end thereof.

I claim—

1. In an apparatus for regulating the flow of liquid, the combination with a container 90 and an outlet valve therefor, of means for opening said valve as the quantity of liquid in said container decreases, and means for preventing the opening movement of said valve as rapidly as the level of the liquid 95 lowers.

2. In an apparatus for regulating the flow of liquid, the combination with a container and an outlet valve therefor, of means controlled by variations in the level of the liquid 100 in said container for opening said valve, and means for resisting the opening movements of said valve whereby said movements are made of less extent than the changes in the liquid level. 105

3. In an apparatus for regulating the flow of liquid, the combination with a container and an outlet valve therefor, of means for adjusting the opening position of said valve when the container is full, means for opening said valve to a greater extent as the quantity of liquid in said container decreases, and means for preventing the opening movement as rapidly as the level of the liquid lowers. 110

4. In an apparatus for regulating the flow of liquid, the combination with a container and an outlet valve therefor, of means controlled by the liquid level in the container for opening said valve, and means for preventing the opening movement of said valve as rapidly as the level of the liquid lowers. 115

5. In an apparatus for regulating the flow of liquid, the combination with a container having an outlet valve, of means controlled 120 by the liquid level in said container for gradually opening said valve to effect a flow of constant volume, and means for adjusting said valve opening means. 125

6. In an apparatus for regulating the flow 130

of liquid, the combination with a container having an outlet valve, of a buoyant member attached to said valve, and a spring acting upon said buoyant member to resist its movement.

5 7. In an apparatus for regulating the flow of liquid, the combination with a container having an outlet valve, of a buoyant member attached to said valve, a spring acting upon said buoyant member to resist its movement, and means for adjusting said spring to control the effective action thereof on said buoyant member.

10 8. In an apparatus for regulating the flow of liquid, the combination with a container having an outlet valve, of an elongated buoyant member attached to the stem of said valve, means for balancing said buoyant member in axial alinement with said valve, and means for adjusting said valve.

15 9. In an apparatus for regulating the flow of liquid, the combination with a container having an outlet valve, of an elongated buoyant member attached to the stem of said valve, means for balancing said buoyant member in axial alinement with said valve, and means for adjusting said valve, the varying degrees of buoyancy imparted

to said buoyant member by the varying liquid level in the container serving to operate said valve to effect a flow of constant volume.

20 10. In an apparatus for regulating the flow of liquid, the combination with a container having an outlet valve, of a buoyant member vertically arranged in said container and attached to the stem of said valve, said buoyant member being of a length at least equal to the distance between the highest and lowest liquid level in said container, means for balancing said buoyant member in axial alinement with said valve, and means for adjusting said valve, the varying degrees of buoyancy imparted to said buoyant member by the varying liquid level in the container acting to vary the cross-sectional area of the opening in said valve to insure at all times a flow of liquid of constant volume.

25 In testimony that I claim the foregoing as my invention, I have signed my name in presence of two subscribing witnesses.

HERMAN NIELSEN.
